(57) **CLAIM**

The ornamental design of a vehicle, as shown and described.

DESCRIPTION

FIG. 1 is a perspective view of a vehicle incorporating my new design, wherein the portions in broken lines form no part of the claimed design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

1 Claim, 4 Drawing Sheets(56)
